5. CONCLUSION

UNITED STATES PATENT OFFICE.

FLOYD D. WENN, OF BINGHAMTON, NEW YORK, ASSIGNOR TO THE BREWER-TITCH-ENER CORPORATION, OF CORTLAND, NEW YORK, A CORPORATION OF NEW YORK.

METHOD AND MACHINE FOR ASSEMBLING AND UNITING FRAME MEMBERS.

Application filed July 30, 1925. Serial No. 47,156.

My invention generically relates to novel machine method for assembling and uniting complementary frame members serving as a moulding for a center medium, said process being performed in connection with a suitable press equipt with operable frame uniting means and with a reciprocating ram provided with improved gripping means adapted to pick up the center medium and 10 convey one of the frame members therewith for assembly purposes; with these outstanding features as a basis, a series of relevant steps are set forth which finally bring about an improved method for uniting said frames 15 around the edge of the center medium. When employed for installing curtain windows, my machine not only mounts complementary grommet-like frame members upon the opposite faces of the curtain or other carrying material, but is further capable of 20 assembling and uniting said frames to bind the curtain about the marginal edge of the center medium.

In the specific embodiment herein disclosed, my machine is shown as equipt with a plurality of separate interconnected crimping tools adapted to be introduced into a suitably shaped hollow expansible male sheet metal frame member subsequent 30 to its assembly into a nestled co-acting female frame member, and by the operation of said tools, simultaneously indenting or crimping said male member into interlocking engagement with the female member at a plurality of spaced points longitudinally disposed along the contour of said members.

Said machine is adapted to unite window sash of frame members and especially such as are commonly used to bind a pane into an 40 automobile curtain, side panels or the like which may be fashioned from leather, fabrics, fibre board or similar carrying material. As applied to vehicle side curtain lights or back curtain sights, a set of complementary frame members are preferably disposed on opposite sides of the pane or other center medium while the inner border of the curtain opening is interposed therebetween for binding purposes, and when 45 these superimposed members are united by means of my interlocking machine, they form a neat and effective tie or binder between the pane and its surrounding curtain fabric.

To accomplish this end, I preferably equip 55 a conventional press with a ram carrying a plurality of crimping tools each rotatably mounted on interconnected spindles, and by imparting an oscillatory movement to said tools, I simultaneously indent a series of 60 spaced crimp cleats between the male and female frame members and thereby minimize the time and cost of mounting curtain light frames when assembled on a productive 65 scale.

A further object of the present invention is to provide for certain improvements intended to supplement those embodied in a cleating machine such as has been disclosed in my copending application Serial No. 70 16,532 filed March 18, 1925. These improvements relate in part to the use of a novel vacuum cup adapted to convey the transparent pane of a curtain sight light and otherwise facilitate the handling and manipulation of the frame members; also to the use of multiple gauge pins which serve to properly locate the cleated sight frame with respect to the back curtain contour. In addition, suitable means are provided for the simultaneous cleating of a plurality of curtain light frames in close association upon a common fabric and thus provide for a style 75 of curtain that is preferred by certain vehicle makers.

Embodying herein are also other features of structure and method steps which insure the desired rapid and proper binding of the frame and its pane into the curtain, all of 80 which will be set forth in detail herein- 85 after.

Reference is had to the accompanying three sheets of drawings which illustrate a specific embodiment of my invention; like characters of reference indicate like parts 90 throughout the several views, and in which drawings:

Fig. 1, represents an elevational side view of my multi-spindled cleating press provided with a ram part equipt with my improved devices and adapted to simultaneously form a series of spaced crimp cleats in one operation.

Fig. 2, is an elevational front view of Fig. 1, and shows the disposition of the centering pins as used for locating the cleated frame in a fixed relation to the curtain shape.

Figs. 3^a, 3^b and 3^c, respectively show a bottom, side and end view of a crimping tool for forcibly expanding and uniting the male and female frame members to bind 5 same into a curtain fabric.

Fig. 4, shows an elevational view of the assembled tool carrier attachable to the bottom of the traveling ram of my machine as taken in partial section along the line 4—4 of 10 Fig. 5.

Fig. 5, represents a top view of said assembled tool carrier except that its retaining plate is removed to better illustrate the manner in which the plural crimping tools may 15 be interconnected by rack and gear means.

Fig. 6, shows a bottom view of Fig. 4 as seen from line 6—6 of Fig. 2, while Fig. 7 is a cross-sectional view of the assembled tool carrier as taken along the line 7—7 of 20 Fig. 5.

Fig. 8, shows a tool carrier similar to Fig. 6, but partially broken away and indicating a modified disposition of the interconnected rotatable crimping tools adapted to simultaneously cleat two separate sight frames 25 into a common curtain fabric.

Fig. 9, is a schematic rear view of an automobile equiped with a back curtain in which multiple sight frames are cleated 30 therein by means of the modified tool carrier disclosed in Fig. 8.

Fig. 10, represents an elevational cross-sectional view of my resilient flared vacuum cup with control appurtenances, serving as 35 a pane gripping and releasing device.

Fig. 11, is a bottom plan view of the pneumatic cup device shown in Fig. 10.

Fig. 12, shows an enlarged vertical fragmental detail of the assembled tool carrier 40 in its uppermost or outward ram position as taken in partial section along line 12—12 of Fig. 6, the inserted male frame member to with the pane being suspended thereon by means of the vacuum cup preparatory to 45 cleating said frame into the female member, which latter member is shown as resting upon the lower die block ready to receive said male member with the curtain fabric initially interposed therebetween.

Fig. 13, is a view similar to Fig. 12 except that the ram has been lowered into its inward position so as to bring the male frame member and said curtain fabric into a nestled assembled position that applies just 55 prior to performing the cleating operation.

Fig. 14, details a screw and spring means serving to resiliently fasten the pressure pad to the main tool carrier plate, as taken along the line 14—14 of Fig. 6.

Referring first to Figs. 1 and 2, these 60 represent a suitable hand operated upright press of the conventional G frame type which in its entirety is designated by the letter A. The frame proper A₁ may be provided with a relatively short vertical guide

way A₂ in which is slidably mounted a traveling head or ram A₃ adapted to overrun the lower transverse face of said guide. The ram may further be equiped with a suitably disposed balance lever A₄, carrying the 70 counterweight A₅. The lower leg of said frame has a foot flange A₆ and this may be fashioned into the relatively long platen or abutment A₇ disposed transversely to the vertical plane of the frame proper. Said 75 platen is suitably spaced with respect to the lower face of the guide A₂ to constitute a frame gap therebetween. Superimposed upon the top face of said platen A₇ is a cover plate or die block A₈ equiped with 80 shallow endless groove or recess A₉ adapted to receive and seat the female member of the two part sheet metal curtain light frame.

It is pointed out that said die block A₈ serves essentially in the capacity of an abutment adapted to oppose the thrust which the ram action is intended to exert upon the complementary frame assembly, and as used in the claims, the term "abutment means" is not intended to be specifically directed toward the structural features shown in the drawings but broadly comprises any similar or equivalent element that might serve the indicated purposes.

Attached to the lower or bottom face of 95 the ram A₃ is a transversely disposed retaining plate A₁₀ which is preferably adapted to travel with said ram. This retaining plate may be equiped with complementary clevises such as A₁₁, each provided 100 with pins adapted to engage the respective links A₁₂ and A₁₃. The upper end of said links pivotally engage the lever arms A₁₃ and A₁₄ respectively, and these arms are tied together by the lever yoke A₁₅ and turn 105 about the fulcrum shaft A₁₆. Said yoke is provided with a manipulating handle A₁₇ and it will be apparent that when said handle is moved from its vertical or normal position (shown in full lines) into its oblique 110 position (shown by dotted lines in Fig. 1) that this will correspondingly shift the sliding ram A₃ and its retaining plate A₁₀, from their outmost position with respect to the block into the lower or inmost position 115 which is also shown by dotted lines in Fig. 1.

The bottom face of the retaining plate A₁₀ is equiped with an attached tool carrier designated in its entirety by the letter B, in 120 Figs. 1 and 2. As is best shown in Figs. 4 to 7 said carrier comprises a spindle holder B, which may be provided with a relatively thin center plate B₂ and offset integral side flanges B₃ and B₄ therefor, disposed to form 125 an open ended channel-like slide slot B₅ which runs lengthwise of said spindle holder. Said flanges may be attached to the retaining plate A₁₀ by means of screws such as B₆ as shown in Fig. 5. Freely mounted 130

within said slot B_5 is a rack slide or reciprocating element B_7 and this may be actuated by means of the shift lever B_8 . As indicated, this lever may be of the bell crank type fulcrumed on an extended portion of one of the side flanges and adapted to be raised and lowered therewith.

One leg of said lever is equipt with a shifting handle B_9 , while its other leg is provided with a projecting pin B_{10} adapted to engage a suitable slot B_{11} by means of which the slide or element B_7 may be shifted between its full and its dotted positions indicated in Fig. 5.

As is best illustrated by Figs. 6, 12 and 13, the spindle holder B_1 is further equipt with a series of spaced holes such as B_{12} , B_{12}' etc. disposed adjacent to the margin of said plate and preferably drilled through their respective reenforcing flanges B_3 and B_4 . The uppermost portion of said holes may be counterbored as B_{13} , B_{13}' etc. to provide for the respective shoulders B_{14} , B_{14}' etc. Mounted within each such plate holes is a forming or crimping tool spindle B_{15} equipt with a shank B_{16} and an enlarged actuating gear segment B_{17} , which latter member is intended to fit into any one of said counterbores and supported by the shoulder such as B_{14} . The shank B_{16} may be recessed into a socket for receiving the crimping tool C and this may be locked in place by the set screw B_{18} .

The preferred type of crimping tool is shown in detail by Figs. 3^a, 3^b and 3^c. The tool proper has a flattened shank portion C_1 adapted to fit into the respective recessed spindle shank B_{16} . This tool is further provided with a reduced neck portion C_2 while its free end is equipt with a head element having oppositely disposed beveled toes C_3 and C_4 respectively. As shown in Fig. 3^a, the overall length " l " of the oblong head is made somewhat greater than its width dimension " b ", while the height " h " on the other hand, is made relatively short for reasons that will appear hereinafter.

As will be understood, the spindles B_{15} together with their inserted tools are intended to oscillate freely within their described mountings. In order to simultaneously operate all the spindles, the slide or reciprocating element B_7 is preferably equipt with inset rack segments which properly engage the respective spindle gear segments such as B_{17} , and simultaneously impart a rotary movement to the aligned tool heads whenever the lever B_8 is shifted within the prescribed limit of travel. If desired, any number of additional tool spindles may be similarly mounted and as will be apparent from Fig. 5, certain of these spindles may be located adjacent to the transverse ends of the spindle holding means B_1 by suitably slotting the rack slide at B_{21} as indicated.

The spindle disposition is preferably such that the elongated head of the respective crimping tools C will align in such fashion that they may readily enter the upturnd mouth of an endless expansible groove part 70 formed in the male member of the curtain light frame.

It will be further observed that the relatively long spindle shank B_{16} projects considerably below the bottom face of either 75 side flange B_3 and B_4 . Intermediate certain of the respective spindles and extending beyond the lower extremities of said crimping tools, a series of inserted upright bridge strips B_{22} depend from the spindle holder 80 B_1 . The spaced strips are also intended to freely enter and align with the mouth of said expansible groove part of the male frame member so as to tightly thrust said groove into close engagement with its coating 85 female frame member prior to interlocking the frame members together.

Referring further to the spindle holder B_1 , this is preferably equipt with a flat hollow pressure pad B_{23} , the opening 90 through which is disposed to freely encircle the downward projecting portions of the various spindle shanks B_{16} , as shown. The bottom face of the pressure pad is preferably mounted so as to fall somewhat below the plane of the distributed crimping tool extremities while the upper face of said pad B_{23} is purposely kept spaced from the lower face of said spindle holder B_1 . The pressure pad is designed to be resiliently hung with 100 respect to holder B_1 by means of a series of adjustable screws such as B_{24} shown in Fig. 14, which screws are threaded in registering holes suitably disposed in the pad B_{23} . The enlarged head of said screws may be supported upon a countersunk shoulder B_{25} formed in the spindle holder as shown, while the lower portion of the screw holes may be recessed to receive the spiral spring such as B_{26} which thrusts against the pressure pad 105 plate and serves to yieldingly hold same in an adjusted spaced relation with respect to the holder B_1 .

The hereinbefore described structural details of my cleating machine are substantially identical with those set forth in my co-pending application previously identified. The present improvements are more particularly directed to the use of a pneumatic vacuum chamber such as is shown in Figs. 10 and 11, which is designated in its entirety by the letter J and serves the ram. Said chamber comprises a resilient flared cup J_1 preferably made of soft rubber, leather or other flexible material, which is provided with an aperture J_2 snugly fitted to the enlarged head J_3' of the cup shank J_3 . The head J_3' is in turn recessed and provided with a hollow plug J_4 having a central hole J_5 and also a communicating transversely disposed hole 115 120 125 130

as indicated. Tightly fitted into the outer or furthermost end of said transverse hole is a relatively long vent tube J_6 of which the free end is equipped with a vent valve J_7 commanding the admission or egress of atmospheric air to or from the inner chamber formed within the cup J_1 and serving as a distant control for breaking the vacuum therein when the cup mouth is properly enclosed.

The outermost edge or rim J_1' of the flared cup is made relatively thin and flexible in order to properly contact and make an air tight joint with respect to the face of the pane which it is intended to grip. When the cup J_1 is firmly pressed against the sight pane E by means of an inward movement of the ram, it will squash the rim J_1' in the fashion shown in Figs. 12 and 13, and thus cause a squeezing out of some of the air previously confined in the enclosed cup chamber. Hence, when the ram thrust between the cup and the pane is relieved, a partial vacuum will have been established within the enclosed cup chamber and this serves to grip and suck the pane against the sealed cup edge J_1' for manipulating and conveying purposes as will be more fully pointed out hereinafter. A release of the pane may be effected at will by pressing down on the vent lever J_8 which then reestablishes the full atmospheric pressure within the cup chamber and breaks the vacuum, thus allowing of selectively conveying the pane with respect to the ram movements.

As to the location of the vacuum cup, it will be observed that this is disposed in a substantially central relation with respect to the desired position of the pane upon the block and that the cup shank J_2 is snugly fitted and made to project through a suitable socket element formed in the spindle holder B_1 as shown in Figs. 12 and 13, while the shank projection engages a longitudinal slot in the slide B_7 and acts as a stop therefor.

As a further refinement in design of my cleating machine, attention is directed to the extension irons K_1 and K_2 which as shown in Figs. 1 and 2, may be attached to any convenient parts of the frame housing for the purpose of supporting a plurality of spaced gauge pins such as K_3 and K_4 , respectively. Said irons are each preferably provided with a longitudinal slot and adjustably fastened to the frame by means of cap screws such as K_5 or the like, which adjusting means permits of shifting the location and pitch between the pins K_3 and K_4 to meet requirements.

When making up side or back automobile curtains in production, it is customary to provide the same with spaced knob eyelets or grommet-like openings (not shown) which are intended to fit over suitable

fastening devices or studs disposed around various parts of the car. In connection with my cleating machine, it is preferred to insert certain of such eyelets into the curtain fabric or provide for similar locating means prior to mounting the curtain light therein, and then so placing and adjusting the described extension irons that their respective pins or co-acting gauge means K_3 and K_4 will readily engage with said predetermined eyelet spacing or other locating means and thus definitely and uniformly position the curtain light with respect to the particular shape given to said fabric.

Taking up now the purpose of my machine as more specifically applied to the cleating of curtain light products, this will be made apparent by further reference to the structural details pertaining to the complementary frames that are to be united about the edge of a pane or other suitable center medium. The details of the frame members which bind the curtain fabric and form a moulding for the edge of its sight pane, have been quite fully described in my co-pending application previously identified, and since these features per se form no essential part of my invention, it will suffice to briefly define the general characteristics of a specific style of article upon which my cleating machine is intended to operate.

In the present disclosures, the letter D in Figs. 12 and 13 is intended to represent in its entirety, an endless sheet metal outer frame member while E is the transparent pane that is to be mounted therein. The frame D may be provided with a cross-sectionally dished shaped offset portion having complementary inturned marginal flanges such as D_2 forming an annular undercut receiving slot D_1 , therebetween which slot may be disposed around the contour of said pane and constitutes the female member of said frame.

In the present window assembly, the curtain fabric F is intended to lie along the parting face of the outer frame D as defined by said inturned flanges. The pane E is centrally disposed and spans the innermost of the inturned flanges and is preferably cushioned by the marginal edges of the interposed fabric F in the manner indicated. The opposite marginal face of the pane E may be gripped by a specially shaped inner or backing frame and this male member of the two part frame is designated as a whole by the letter G .

Said inner sheet metal frame comprises a bead-like pane engaging flange G_1 which need not however be made endless as are the remaining parts of this member; instead said flange G_1 is preferably cut away along one of the frame sides so as to form a gap to permit of the endwise renewal of the interlocked pane such for instance as is disclosed

in the Bishop Patent 1,537,739 granted May 12, 1925. The inner frame G is further provided with a relatively narrow grooved male part G₄ comprising a set of side walls 5 G₅ and G₆ which are disposed substantially normal to the face of the pane as shown and tied together by the transverse wall G₇ serving to close the bottom of said groove. The proper overall face dimension of this bottom wall is determined by width of the female part or receiving slot D₁ of the outer frame, the intent being that said trough shaped grooved male part shall co-act with and be adapted to enter any desired shape 10 that may be given to the slotted female part or parts.

When completely assembled upon the curtain fabric, the two co-acting frame members as applied to a curtain window installation are finally brought into the relation indicated in Fig. 13. Prior to interlocking said members D and G, they are firmly clamped or sprung together by means of a superimposed ram thrust, thus interlacing 20 and making the curtain fabric take a circuitous path about the nestled male and female parts in the manner illustrated.

While held in this strained or sprung relation, the male and female frame members 30 may be interlocked by means of the described crimping tools designed to be introduced into the upturned open mouth of said male groove. The width "b" of the tool toes is made somewhat smaller than the spacing between the side walls G₅ and G₆ of the grooved male member while the length "l" 35 of said tool is made somewhat larger, to the end that when a partial turn is given to the shank C₁ of any inserted tool subsequent to the assembling of the nestled members D and G, this will cause said toes to simultaneously indent or forcibly expand the side walls and it will be seen that its overall 40 width is now greater than that of the female slot D₁ and positively unites said frame together. It will be apparent that this cleating operation also securely binds the border of interposed fabric opening to the assembled frame and that it is preferred to use a plurality of spaced cleats for uniting the frame 45 members to insure against pulling the curtain out of its binding.

Having described the principal features 50 of structure of my machine and also a specific style of product upon which it is intended to operate, the function of my machine may be traced as follows:

Assuming the manipulating handle A₁₇ to 55 stand in its full-lined or raised outmost position shown in Fig. 1 and that the tool carrier is equipped with the described appurtenances, then the press is ready to receive the complementary frame and the successive installation steps as applied to a curtain window 60 may be described as follows: The first

step consists in seating the outer frame or female member D in the recess of the die block A₈, with the transparent pane E set into its interposed position and the inner frame or male member G superimposed 70 thereon, thus assuming an incomplete assembled position not unlike that shown in Fig. 13 except for the absence of the interposed curtain fabric F. The manipulating handle A₁₇ is then firmly pulled down to 75 bring the ram into its inward position, which causes the rim of the vacuum cup J₁ to be squashed against the uppermost face of the underlying pane and grip the same. By the subsequent raising of the handle A₁₇, both 80 the pane and the top-most or inner frame G are thereby picked up and conveyed with the ram to assume the spaced relation with respect to said seated outer frame D that is shown in Fig. 12 and this operation constitutes the second step in my method. 85

As a third step the curtain fabric F is thereupon introduced and interposed between the separated frame members and preferably made to lay upon the parting face 90 D₂ of the lower frame D as indicated by Fig. 12. Any desired fixed position for the inserted curtain light frames may now be located by slipping certain of the described fabric eyelets over the respective adjusted 95 gauge pins K₃ and K₄.

As a fourth step, the lever A₁₇ is again pulled down into its inmost position as shown in dotted lines by Fig. 1; this will cause the carrier together with its inserted 100 male frame member G and the pane E to be conveyed into the assembled position shown by Fig. 13. In the present style of frame, the fabric thus becomes snugly interwoven between the nestled male part of the 105 frame G and its co-acting undercut female groove D₁, and by further pulling down firmly on said lever, the spaced bridge strips B₂₂ are intended to snugly press against the bottom groove wall B₇ and hold the two 110 frame members in clamped engagement preparatory to uniting the frames into interlocking relation in the fashion shown in Fig. 14. It will be seen that the pressure pad B₂₃ will at the same time have been pressed up 115 closer toward the spindle holder B₁ and that said pad is made to firmly press down upon the interposed fabric around the entire perimeter of said nestled frames, but such refinements constitute no essential feature in 120 the fourth step of the described operations.

While the frames are held in said clamped relation, the complementary frames are 125 united about their interposed elements and this comprises the fifth step; in the present instance, said step is performed by drawing the shifted lever B₈ laterally into the dotted position shown in Fig. 5, which in turn simultaneously partially rotates the various tool toes such as C₃ and C₄ and serves 130

to indent or crimp spaced interlocking cleats between the male and female parts of the co-acting frame D and G. At this juncture, the valve lever J_8 is depressed to open the vent valve J_7 which breaks the vacuum within the flared suction cup J_1 and relieves its grip on the pane.

The lever B_8 is now again returned into its normal or full-lined position and this permits the unhampered withdrawal of the tool carrier and its associated parts from the upturned mouth of the grooved male frame part G_4 . Thereupon the manipulating lever A_{17} may be raised into its normal or outmost position which then completes the curtain window installation as performed by my machine, and allows the curtain fabric together with its inserted sight pane to be freely removed from the jaws of the press, all as is more succinctly set forth in the appended method claims. If desired, the manipulating lever A_{17} and the shifter lever B_8 may readily be interlocked to facilitate the proper sequence of the described operations, suitable devices to accomplish this purpose being set forth in the aforesaid pending application and need not here be elaborated upon.

In certain cases especially when a sight pane is to be installed into the conventional fabric curtain; it is preferred to introduce such fabric between the complementary frame members in an uncut condition as regards its sight opening, although it may be expedient to cut cross slits in said pane spanning curtain portion for the purpose of facilitating the described interlaced binding of the inner fabric border into the frame members, all without drawing inwardly or wrinkling that portion of the fabric lying outside of the frame perimeter. After otherwise completing the frame assembly in the press, the curtain fabric when left to span the pane, may thereupon be trimmed to make the curtain opening conform to the inner contour of the frame and thus remove obstruction to the normal transparency of the pane, and when resorted to, such trimming operation constitutes a final supplementary step in my method of installing curtain lights.

In the event that the use of my machine should be confined to mounting and uniting moulding-like complementary frames about the edge of a center medium, it will be understood that the necessary installation steps will be substantially similar to those heretofore set forth except in so far as the omission of the inserted curtain element may 55 modify or simplify the described operations. 60

As a further modification of the described type of machine for cleating single curtain light frames, it is pointed out that the described disposition of the plural tool spindles 65 may readily be arranged to simultaneously

cleat two separate curtain light frames into a common back curtain fabric. If preferred, the carrier may for this purpose be provided with two separate interconnected slide racks such as B_7' and B_7'' suitably mounted alongside each other in the fashion shown in Fig. 8, which results in producing a double curtain light frame assembly such as that indicated in Fig. 9 by the designation D' and D'' , it being apparent that the shape of the frame may be given any contour that the purchaser may prefer. In this instance, the two slide racks are interlocked through a series of intermediate gears such as B_{17}' which then connects said racks B_7' and B_7'' and cause them to travel in unison when manipulated from the common shifter lever B_8' . It will be seen that each of the duplicate carrier parts are preferably provided with independent vacuum cups J_1' and J_1'' , the chambers of which communicate through the common vent pipe J_6' shown in dotted outline in Fig. 8. This pipe is in turn commanded by a single vent valve J_7' , but in other respects the carrier appurtenances remain substantially similar to those previously described without essentially affecting their normal mode of operation. It will also be apparent that when a plurality of curtain light frames are to be simultaneously cleated, it is expedient to provide for duplicate die blocks for the frame platen in order that the assembled frame may properly align with their respective tool carrier appurtenances.

My machine is likewise applicable to uniting frames each provided with a series of co-acting male and female parts instead of using only one continuous groove as has been more specifically described herein. 105 Furthermore, it is not essential that the curtain be fashioned from fabric and like flexible materials since the method and devices herein set forth may readily be used to bind a pane into a curtain made of fibre board or other stiff carrying materials, but in that event it is expedient to initially cut the curtain opening sufficiently large to freely encompass and clear the nestled male and female frame parts, and which are then merely clamped between the outermost flanges of the complementary frames. It will also be understood that various changes in the details of my machine may be resorted to, such as making the same power driven instead of hand operated and the like, all without departing from the spirit and scope of my invention, heretofore described and more particularly set forth in the appended claims. 120 125

Claims:

1. The method of manipulating a pair of members adapted to mount a center medium therebetween, said method being performed by a machine equipt with an abutment 130

means and with a cooperating movable means served by assembly manipulating devices adapted to contact and pick up the center medium; said method consisting in 5 the following steps, viz: firstly, introducing between said movable means and the abutment, both members in superimposed relation with the medium inserted therebetween; secondly, picking up the center 10 medium and thereby conveying the topmost member therewith.

2. The method of assembling a pair of members adapted to mount a center medium therebetween, said method being performed 15 by a machine equiped with an abutment means and with cooperating movable means served by assembly manipulating devices adapted to detachably pick up the center medium at will, said method consisting in 20 the following steps, viz; firstly, introducing between said movable means and the abutment, both of the aforesaid members in superimposed relation with the medium inserted therebetween; secondly, picking up 25 the center medium and thereby conveying the topmost member therewith; lastly, returning said topmost member and the center medium into assembled position and releasing the hold on the center medium.

3. In a machine for uniting complementary frame members serving to grip a pane therebetween and bind the edge of a sight pane into a curtain, said machine being equiped with abutment means adapted to seat one of said frame members upon which the other member is superimposed with the pane inserted therebetween, and being further equiped with a ram adapted to intermittently move toward and away from said 40 abutment, a suction cup means serving the ram adapted to pick up and convey the pane together with the other or topmost of said frame members prior to uniting said frames for the purpose of permitting a curtain to be interposed between the frame members while said other frame and the pane is conveyed away from said seated frame member, and means associated with said ram adapted to unite said frame members about both the pane and said interposed fabric subsequent to returning the other frame member and the pane into completely assembled relation with respect to said seated frame member and the curtain.

4. In a machine for interlocking complementary frame members serving to bind a medium therebetween of which frame one member is provided with a female part or parts while the other is provided with hollow expansible male part or parts respectively adapted to nestle within the female part or parts, said machine being equiped with abutment means and a tool carrier, the latter comprising a plurality of interconnected spindles and simultaneous actuating

means therefor, means for moving said carrier toward and away from said abutment, a suction cup means for the tool carrier adapted to grip and convey said medium therewith for frame assembly purposes, and 70 a crimping tool for each of said spindles, said tool being adapted to enter an expandable frame part and by the turning thereof serving to indent or expand said frame members into interlocking relation about 75 the assembled medium.

5. The method of assembling a pair of members adapted to mount a center medium therebetween, said method being performed by a machine equiped with an abutment 80 means and with cooperating movable means served by a pneumatic chamber device comprising a resilient vacuum cup adapted to contact and pick up the center medium, said chamber being commanded by vent 85 means adapted to break the hold of said cup and release the medium, said method consisting in the following steps, viz: firstly, introducing between said movable means and the abutment, both of the aforesaid 90 members in superimposed relation with the medium inserted therebetween; secondly, picking up the center medium and thereby conveying the topmost member therewith; lastly, returning said topmost member and 95 the medium into assembled position and operating the vent means to release the hold of the vacuum cup on the center medium.

6. In a machine for uniting a set of complementary binding frame members about 100 the edge of a curtain sight pane, said machine being equiped with abutment means seating one of said frame members with the pane and the other member superimposed thereon in partially assembled relation, a ram adapted to be intermittently moved toward and away from said abutment, a vacuum chamber means serving said ram and comprising a resilient cup element adapted to contact the pane on its inward stroke and convey the pane and the topmost of said frame members with said ram on its outward stroke for the purpose of permitting a curtain to be interposed while said frame members are separated and said ram serving 110 upon its subsequent inward stroke to completely reassemble said frame members and clamp the pane and interposed curtain therebetween, and means for uniting said frame members while subject to said clamping 115 action on part of the ram.

7. In a machine for uniting a set of complementary frame members about the edge of a curtain sight pane, said machine being equiped with abutment means seating one of 125 said frame members with the pane and the other member superimposed thereon in assembled relation, a ram adapted to be intermittently moved toward and away from said abutment, said ram being provided with 130

gripping means for conveying the pane and the topmost of said frame members with said ram on its outward stroke and serving to separate said frame member to admit of inserting a curtain therebetween, said ram serving upon its inward stroke to re-assemble the frame members and impose a clamping thrust upon both the interposed fabric and pane, and operable means for uniting said completed frame assembly at a plurality of spaced points.

8. In a machine for uniting a set of complementary curtain light frame members and binding a curtain therebetween, said machine being equipt with abutment means and a reciprocating ram provided with operable frame uniting means adapted to move toward said abutment, a set of spaced gauge pins with which a curtain is adapted to engage and fixedly locate said frame members relative to the shape of the curtain, and means for actuating the frame uniting means serving to fasten said frame members together about the interposed curtain.

9. In a machine for uniting a set of complementary frame members and binding a curtain therebetween, said machine being equipt with abutment means and a reciprocating ram adapted to move toward said abutment for the purpose of uniting said frame members, a set of spaced gauge pins laterally disposed with respect to said block and with which pins a curtain is adapted to engage for fixedly locating said frames with respect to the curtain contour, means for adjustably altering the location of said pins to suit the disposition of said curtain, and means for uniting said frame members about the interposed curtain.

10. In a machine for simultaneously uniting a plurality of complementary frame members about the edge of their respective curtain sight panes, said machine being equipt with abutment means adapted to seat thereon a plurality of frame members with their panes and complementary frame members respectively superimposed in a partially assembled relation, a ram adapted to intermittently move toward and away from said abutment, said ram being provided with gripping means for picking up both of said panes serving to convey the panes and the topmost of the respective frame members with said ram on its outward stroke to admit of inserting a common curtain between said separated plural frame members, said ram serving upon its inward stroke to respectively reassemble said plural frame members and impose a thrust therebetween and upon the interposed curtain and the respective panes, and means for simultaneously uniting the respective clamped frame members in their completely assembled relation upon said common curtain.

11. In a machine for simultaneously uniting a plurality of complementary frame members about the edge of their respective curtain sight panes, said machine being equipt with abutment means adapted to seat thereon a plurality of frame members respectively superimposed in assembled relation, a ram adapted to intermittently move toward and away from said abutment, a vacuum chamber means serving the ram adapted to grip the respective panes and convey said panes and their respective topmost frame members therewith, a conduit means establishing communication between said chambers, a control means for venting said conduit to break the vacuum in said chamber means and release said panes from the ram, said ram on its outward stroke serving to separate the panes and their respective frames from their complementary seated members to admit of inserting a common curtain between the plural frame members and said ram serving on its inward stroke to respectively reassemble said plural frame members and impose a thrust therebetween and upon the interposed curtain and their respective panes, and means for simultaneously uniting the respective clamped frame members in their completely assembled relation upon said curtain.

12. In a machine for uniting a plurality of complementary frame members about their respective curtain sight panes, said machine being equipt with abutment means and a reciprocating ram provided with frame uniting appurtenances adapted to intermittently move toward said abutment and simultaneously unite the respective frame members and bind a plurality of transparent sight openings in a common curtain.

13. In a machine for uniting a set of complementary endless frame members adapted to encompass the marginal edge of a transparent pane and serving to bind the same into a curtain, said machine comprising abutment means on which one of said frame members is adapted to seat and further comprising a reciprocating ram adapted to move toward said abutment and impose a thrust upon the other of said frame members when placed upon the first named frame with the curtain and the pane interposed in assembled relation, and means for uniting said clamped frame members about both said pane and its surrounding curtain.

14. In a machine for uniting a set of complementary endless frame members adapted to encompass the marginal edge of a transparent pane and serving to bind the same into a curtain for sight purposes, said machine comprising abutment means on which one of said frame members is adapted to rest and further comprising a reciprocating ram adapted to move toward said abutment

- and exert a thrust between said frame members when placed upon the first named frame member with the curtain and the pane interposed in assembled relation, said curtain being initially uncut for its sight opening and adapted to span one face of the pane, and means for uniting said clamped frame members about said curtain, said curtain being trimmed along the interior contour of one of the adjacent frame members to provide for a sight opening therethrough subsequent to the uniting of said members.
15. In a machine for uniting a set of complementary curtain light frame members and binding a curtain therebetween, said machine being equiped with abutment means and a reciprocating ram adapted to intermittently move toward said abutment for frame uniting purposes, a curtain being interposed between said frame members having positioning means disposed in a predetermined relation to the shape of said curtain, spaced gauge pins adapted to respectively engage said positioning means and serving to fixedly locate said frame members upon the interposed curtain, and means for uniting said frame members about said positioned curtain.
16. The method of assembling sash-like frame members adapted to grip a medium and bind the medium into a carrying material, said method being performed by a machine equiped with operable frame uniting means, an abutment means, and co-operating movable means having gripping means adapted to pick up and convey the center medium therewith, said method consisting in the following steps, viz: firstly, placing upon said abutment the set of frame members with said medium disposed therebetween in overlapping relation to the uppermost frame member; secondly, picking up said medium together with said topmost frame member and conveying them away from the bottommost frame member; thirdly, introducing a carrying material between said separated frame members; fourthly, further conveying the suspended frame member and the medium down upon said interposed carrying material and completing the assembly; and lastly, actuating the uniting means to secure said frame members and bind the medium into the carrying material.
17. The method of installing a window assembly in a curtain, which assembly comprises a pair of frame members adapted to grip a pane or other center medium and bind the margin thereof into a curtain, said method being performed by a machine equiped with operable frame uniting means, an abutment means, and co-operating movable means having gripping means adapted to pick up and convey said pane away from or toward said abutment, said method consisting in the following steps, viz: firstly, placing upon said abutment said pair of frame members in superimposed relation with the pane disposed therebetween; secondly, picking up the pane together with the topmost of said frame members and conveying them away from the bottommost frame member; thirdly, introducing a curtain between said separated frame members; fourthly, further conveying the suspended frame member and pane down upon the interposed curtain and completing the assembly; and lastly, actuating the uniting means to secure said frame members and bind the curtain.
18. The method of installing a window assembly in a curtain, which assembly comprises a pair of endless frame members adapted to encompass and grip a pane or other center medium therebetween for mounting the same into a curtain, said method being performed by a machine equiped with operable frame uniting means, an abutment means, and co-operating movable means having gripping means adapted to pick up and convey said pane therewith said method consisting in the following steps, viz: firstly, placing upon said abutment the pair of frame members in superimposed relation with the medium disposed therebetween; secondly, picking up said medium together with the topmost of said frame members and conveying them away from the bottommost frame member; thirdly, introducing a curtain between said separated frame members, said inserted curtain being adapted to span the frame opening; fourthly, further conveying the suspended frame member and medium down upon said interposed curtain to complete the assembly; fifthly, actuating the uniting means to secure said frame members and bind the medium into the curtain, and lastly, trimming the curtain portion which spans the frame opening to expose the medium.

In testimony whereof, I have herewith set my hand this 27th day of July, 1925.

FLOYD D. WENN.
